(57) **ABSTRACT**

A liquid container includes a liquid container portion and a liquid inlet portion. The liquid inlet portion is connected with the liquid container portion and configured to pour liquid into the liquid container portion. The liquid container portion includes a bottom wall, a liquid inlet portion-forming wall that is located above the bottom wall and at which the liquid inlet portion is arranged, a visual recognition wall, an opposite wall opposite the visual recognition wall, and a partition wall. The visual recognition wall is a wall that extends in a direction intersecting the bottom wall and the liquid inlet portion-forming wall and through which the liquid in the liquid container portion is visible from outside. At least a part of the partition wall is located between the visual recognition wall. The opening is an intersecting part at which the liquid inlet portion intersects with the liquid inlet portion-forming wall.

**LIQUID CONTAINER, LIQUID CONTAINER
UNIT, LIQUID EJECTION SYSTEM AND
LIQUID EJECTION APPARATUS**

This application is a continuation application of U.S. patent application Ser. No. 14/779,035, filed on Sep. 22, 2015. This application claims priority to Japanese Patent Application No. 2014-003960 filed on Jan. 14, 2014. The entire disclosures of U.S. patent application Ser. No. 14/779,035 and Japanese Patent Application No. 2014-003960 are hereby incorporated herein by reference.

TECHNICAL FIELD

The present invention relates to a liquid container, a liquid container unit, a liquid ejection system, a liquid ejection apparatus and the like.

BACKGROUND ART

An inkjet printer has conventionally been known as one example of a liquid ejection apparatus. The inkjet printer ejects ink as one example of a liquid from an ejection head onto a printing medium such as printing paper, so as to implement printing on the printing medium. A known configuration of the inkjet printer causes ink stored in a tank as one example of a liquid container to be supplied to the ejection head. This tank is provided with an ink inlet port. The user is allowed to refill ink from the ink inlet port into the tank (see, for example, JP 2012-51309A). In the description below, the configuration that the liquid container such as tank is added to the liquid ejection apparatus such as inkjet printer may be called liquid ejection system.

SUMMARY

Technical Problem

The tank described in JP 2012-51309A has a translucent tank main body. This configuration enables the user to visually check the amount of ink contained in the tank from outside. The tank has an upper limit line provided in part of wall portions constituting the tank main body. This configuration enables the user to pour ink from an inlet port into the tank, while visually checking the amount of ink contained in the tank via the wall portion with the upper limit line. The wall portion with the upper limit line is called visual recognition portion. When the liquid level of ink contained in the tank reaches the upper limit line, the user can recognize that the amount of ink in the tank reaches its upper limit. In the tank described in JP 2012-51309A, however, the visual recognition portion is located near to the inlet port. When ink is poured from the inlet port into the tank, the poured ink may thus adhere to the visual recognition portion inside of the tank. This deteriorates the visibility of the visual recognition portion and makes it difficult for the user to recognize the amount of ink contained in the tank. Accordingly, the conventional liquid container has difficulty in recognizing the amount of the liquid.

Solution to Problem

In order to solve at least part of the problems described above, the invention may be implemented by the following aspects or embodiments.

According to one aspect of the invention, a liquid container includes a liquid container portion and a liquid inlet

2

portion. The liquid container portion is configured to contain a liquid. The liquid inlet portion is connected with the liquid container portion and allows the liquid to be poured into the liquid container portion. The liquid container portion includes a bottom wall, a liquid inlet portion-forming wall that is located above the bottom wall and at which the liquid inlet portion is arranged, a visual recognition wall that extends in a direction intersecting with the bottom wall and the liquid inlet portion-forming wall and through which the liquid in the liquid container portion is visible from outside, an opposite wall opposite to the visual recognition wall, and a partition wall. At least a part of the partition wall is located between an opening and the visual recognition wall, and the opening is an intersecting part at which the liquid inlet portion intersects with the liquid inlet portion-forming wall.

According to the aspect of the invention, the partition wall includes a first partition wall that is located between the visual recognition wall and the opposite wall and extends in a direction from the liquid inlet portion-forming wall toward the bottom wall, and a second partition wall that is located between the liquid inlet portion-forming wall and the bottom wall and extends in a direction from the visual recognition wall toward the opposite wall. A part of the second partition wall is located below the opening in a vertical direction.

According to the aspect of the invention, the second partition wall is inclined to be closer to the bottom wall as approaching from the visual recognition wall toward the opposite wall.

According to the aspect of the invention, the partition wall has a cylindrical structure that extends from the intersecting part toward the bottom wall.

According to the aspect of the invention, a lower limit mark that indicates a lower limit of a liquid amount in the liquid container portion is disposed on the visual recognition wall.

According to the aspect of the invention, an upper limit mark that indicates an upper limit of a liquid amount in the liquid container portion is disposed on the visual recognition wall.

According to the aspect of the invention, only an area of a part of the visual recognition wall has liquid repellency.

According to the aspect of the invention, only an area of a part of the visual recognition wall has liquid repellency, and the area includes the lower limit mark.

According to the aspect of the invention, only an area of a part of the visual recognition wall has liquid repellency, and the area includes the upper limit mark.

According to another aspect of the invention, a printer includes the liquid container according to the above aspect of the invention, and a liquid ejection head. The liquid container is contained in a case of the printer, and the case has a window portion that faces the visual recognition wall of the liquid container portion.

BRIEF DESCRIPTION OF DRAWINGS

FIG. 1 is a perspective view illustrating a liquid ejection system according to a first aspect;

FIG. 2 is a perspective view illustrating the liquid ejection system of the first aspect;

FIG. 3 is a perspective view illustrating the liquid ejection system of the first aspect;

FIG. 4 is a perspective view illustrating a mechanism unit of a printer according to the first aspect;

FIG. 5 is an exploded perspective view illustrating a tank of Embodiment 1;

FIG. 6 is a side view of the tank of Embodiment 1 seen from a sheet member side;

FIG. 7 is a perspective view illustrating a casing of Embodiment 1;

FIG. 8 is a perspective view illustrating the casing of Embodiment 1;

FIG. 9 is a sectional view illustrating an ink inlet portion and an air communication port of the tank of Embodiment 1 taken on an XZ plane;

FIG. 10 is a side view of the tank of Embodiment 1 seen from the sheet member side;

FIG. 11 is an exploded perspective view illustrating a tank of Embodiment 2;

FIG. 12 is a sectional view illustrating an ink inlet portion and an air communication port of the tank of Embodiment 2 taken on the XZ plane;

FIG. 13 is a diagram illustrating a third wall of the tanks of Embodiment 1 and Embodiment 2;

FIG. 14 is a diagram illustrating the third wall of the tanks of Embodiment 1 and Embodiment 2;

FIG. 15 is a diagram illustrating the third wall of the tanks of Embodiment 1 and Embodiment 2;

FIG. 16 is a diagram illustrating the third wall of the tanks of Embodiment 1 and Embodiment 2;

FIG. 17 is a perspective view illustrating a multifunction printer according to a second aspect;

FIG. 18 is a perspective view illustrating the multifunction printer of the second aspect;

FIG. 19 is a perspective view illustrating a printer according to the second aspect; and

FIG. 20 is a perspective view illustrating a mechanism unit of the printer of the second aspect.

DESCRIPTION OF EMBODIMENTS

The following describes a liquid ejection system including an inkjet printer (hereinafter called printer) as one example of the liquid ejection apparatus according to one aspect with reference to the drawings. The respective drawings may employ different scales to show the respective configurations and members in recognizable sizes.

[First Aspect]

As shown in FIG. 1, a liquid ejection system 1 according to a first aspect includes a printer 3 as one example of the liquid ejection apparatus and a tank unit 5. The printer 3 has a first casing 6. The first casing 6 forms the outer shell of the printer 3. The tank unit 5 has a second casing 7 and a plurality of (two or more) tanks 9. The first casing 6 and the second casing 7 form the outer shell of the liquid ejection system 1. The tank 9 is one example of the liquid container. The liquid ejection system 1 is configured to perform printing on a printing medium P such as printing paper with ink as one example of the liquid.

XYZ axes as coordinate axes that are orthogonal to one another are shown in FIG. 1. The XYZ axes are also added as appropriate in subsequent drawings. With respect to each of the XYZ axes, the direction of arrow represents + direction (positive direction), and the opposite direction to the direction of arrow represents - direction (negative direction). In the use state of the liquid ejection system 1, the liquid ejection system 1 is placed on a horizontal plane defined by the X axis and the Y axis. In the use state of the liquid ejection system 1, the Z axis is the axis orthogonal to the horizontal plane, and the -Z-axis direction is downward in the vertical direction.

A mechanism unit 10 (shown in FIG. 10) of the printer 3 is placed in the first casing 6. The mechanism unit 10 is a

mechanism part configured to perform a printing operation in the printer 3. The details of the mechanism unit 10 will be described later. As shown in FIG. 1, the plurality of tanks 9 are placed in the second casing 7 and are respectively provided to contain inks used for printing. According to this aspect, four tanks 9 are provided. The four tanks 9 respectively contain different inks. This aspect employs four different inks, i.e., black, yellow, magenta and cyan. There are one tank 9 to contain black ink, one tank 9 to contain yellow ink, one tank 9 to contain magenta ink and one tank 9 to contain cyan ink. In the liquid ejection system 1, the plurality of tanks 9 are placed outside of the first casing 6. Accordingly, in the liquid ejection system 1, the plurality of tanks 9 are not placed inside of the first casing 6 arranged to cover the mechanism unit 10.

The printer 3 is provided with a paper ejection portion 11. In the printer 3, the printing medium P is discharged from the paper ejection portion 11. In the printer 3, a surface where the paper ejection portion 11 is located is a front surface 13. The printer 3 also has an operation panel 17 on a top surface 15 intersecting with the front surface 13. The operation panel 17 includes a power button 18A and other operation buttons 18B. The tank unit 5 is provided on a side surface 19 of the first casing 6 intersecting with the front surface 13 and the top surface 15. The second casing 7 has windows 21. The windows 21 are provided on a side surface 27 of the second casing 7 intersecting with its front surface 23 and top surface 25. The windows 21 have optical transparency. The four tanks 9 described above are provided at positions overlapping the windows 21. This enables the operator using the liquid ejection system 1 to visually check the four tanks 9 via the windows 21. According to this aspect, the windows 21 are provided as openings formed in the second casing 7. The operator can visually check the four tanks 9 via the windows 21 that are the openings. The windows 21 are, however, not limited to the openings but may be made of a material having optical transparency.

According to this aspect, at least part of an area of each tank 9 facing the window 21 has optical transparency. The ink contained in the tank 9 is visible through this area of each tank 9 having optical transparency. Accordingly, this enables the operator to visually recognize the four tanks 9 via the windows 21 and thereby visually check the amounts of inks in the respective tanks 9. In other words, at least part of the area of the tank 9 facing the window 9 serves as the visual recognition portion from which the amount of ink is visible. Each tank 9 has an upper limit mark 28 indicating an upper limit of ink amount and a lower limit mark 29 indicating a lower limit of ink amount, in the area facing the window 21. The operator recognizes the amount of ink remaining in each tank 9 using the upper limit mark 28 and the lower limit mark 29 as indications. The first casing 6 and the second casing 7 are provided as separate members. According to this aspect, the second casing 7 is thus separable from the first casing 6 as shown in FIG. 2. The second casing 7 is joined with the first casing 6 by means of mounting screws 31. The second casing 7 covers at least part of the four tanks 9, for example, the front surface, the top surface and the side surface as shown in FIG. 2.

The tank unit 5 has a support frame 32. The four tanks 9 are supported by the support frame 32. The support frame 32 is provided as a separate member from the first casing 6. According to this aspect, the support frame 32 is thus separable from the first casing 6 as shown in FIG. 3. The support frame 32 is joined with the first casing 6 by means of mounting screws 33. As described above, the tank unit 5

(shown in FIG. 1) is mounted to the outside of the first casing 6 according to this aspect.

As shown in FIG. 4 that is a perspective view illustrating the mechanism unit 10, the printer 3 includes a printing assembly 41 and supply tubes 43. The printing assembly 41 includes a carriage 45, a print head 47 and four relay units 49. The print head 47 and the four relay units 49 are mounted on the carriage 45. The supply tubes 43 are flexible and are provided between the tanks 9 and the relay units 49. The ink contained in the tank 9 is supplied through the supply tube 43 to the relay unit 49. The relay unit 49 transfers the ink which is supplied from the tank 9 through the supply tube 32, to the print head 47. The print head 47 ejects the supplied ink in the form of ink droplets.

The printer 3 also has a medium feeding mechanism (not shown) and a head carrying mechanism (not shown). The medium feeding mechanism drives a feed roller 51 with the power from a motor (not shown), so as to feed the printing medium P along the Y-axis direction. The head carrying mechanism transmits the power from a motor 53 via a timing belt 55 to the carriage 45, so as to carry the carriage 45 along the X-axis direction. The print head 47 is mounted on the carriage 45. The print head 47 is thus movable in the X-axis direction via the carriage 45 by the head carrying mechanism. The print head 47 is supported on the carriage 45 in the state that the print head 47 faces the printing medium P. The medium feeding mechanism and the head carrying mechanism cause ink to be ejected from the print head 47 while changing the position of the print head 47 relative to the printing medium P, so as to implement printing on the printing medium P.

The following describes some embodiments of the tanks 9. In the description below, for the purpose of discrimination of the tanks 9 of respective embodiments, different alphabets are added in different embodiments as suffixes to the signs as appropriate.

Embodiment 1

The following describes a tank 9A according to Embodiment 1. As shown in FIG. 5, the tank 9A has a casing 61A as one example of the tank main body and a sheet member 63. The casing 61A is made of a synthetic resin such as nylon or polypropylene. The sheet member 63 is made of a synthetic resin (for example, nylon or polypropylene) in a film-like shape and has flexibility. According to this embodiment, the sheet member 63 has optical transparency. The tank 9A is formed by joining the casing 61A with the sheet member 63. The casing 61A has a joint portion 64. The joint portion 64 is hatched for the clarity of the configuration in FIG. 5. The sheet member 63 is joined with the joint portion 64 of the casing 61A. According to this embodiment, the casing 61A and the sheet member 63 are joined with each other by welding.

As shown in FIG. 6, the tank 9A has a container portion 65 and a communicating portion 67. The communicating portion 67 includes an air chamber 68 and a communicating path 73. In the tank 9A, ink is contained in the container portion 65. In FIG. 6, the tank 9A is seen from the sheet member 63-side, and the casing 61A is illustrated through the sheet member 63. The container portion 65, the air chamber 68 and the communicating path 73 are parted from one another by the joint portion 64. The casing 61A has a first wall 81, a fourth wall 84, a fifth wall 85, a second wall 82, a third wall 83, a sixth wall 86, a seventh wall 87 and an eighth wall 88. The air chamber 68 and part of the communicating path 73 are placed on an opposite side of the fifth

wall 85 opposite to the container portion 65-side. In the plan view of the first wall 81 from the sheet member 63-side, the container portion 65 is surrounded by the fourth wall 84, the fifth wall 85, the second wall 82 and the third wall 83. The third wall 83 is arranged to face the window 21 of the second casing 7. In other words, the third wall 83 includes the area having optical transparency in the tank 9A.

In the plan view of the first wall 81 from the sheet member 63-side, the air chamber 68 is surrounded by the fifth wall 85, the sixth wall 86, the seventh wall 87 and the eighth wall 88. The first wall 81 of the container portion 65 is identical with the first wall 81 of the air chamber 68. In other words, the container portion 65 and the air chamber 68 share the first wall 81 according to this embodiment. The fourth wall 84, the fifth wall 85, the second wall 82 and the third wall 83 respectively intersect with the first wall 81 as shown in FIG. 7. The fifth wall 85 is located on the +Z-axis direction side of the fourth wall 84. The fourth wall 84 and the fifth wall 85 are arranged to face each other across the first wall 81. The third wall 83 is located on the +X-axis direction side of the second wall 82. The second wall 82 and the third wall 83 are arranged to face each other across the first wall 81. The second wall 82 is arranged to intersect with both the fourth wall 84 and the fifth wall 85. The third wall 83 is also arranged to intersect with both the fourth wall 84 and the fifth wall 85.

The fourth wall 84, the fifth wall 85, the second wall 82 and the third wall 83 are protruded in the -Y-axis direction from the first wall 81. A recess 91 is accordingly formed by the first wall 81 as main wall and the fourth wall 84, the fifth wall 85, the second wall 82 and the third wall 83 extended in the -Y-axis direction from the main wall. The recess 91 is formed to be concave in the +Y-axis direction. The recess 91 is open in the -Y-axis direction, i.e., toward the sheet member 63 (shown in FIG. 5). In other words, the recess 91 is provided to be concave in the +Y-axis direction or more specifically to be concave in an opposite direction opposite to the sheet member 63-side (shown in FIG. 5). When the casing 61A is joined with the sheet member 63, the recess 91 is closed by the sheet member 63, so as to form the container portion 65. The first wall 81 to the eighth wall 88 are not limited to flat walls but may have some concavo-convex shapes.

As shown in FIG. 6, the sixth wall 86 is protruded from the fifth wall 85 in an opposite direction of the fifth wall 85 opposite to the fourth wall 84-side, i.e., toward the +Z-axis direction side of the fifth wall 85. The seventh wall 87 is also protruded from the fifth wall 85 in an opposite direction of the fifth wall 85 opposite to the fourth wall 84-side, i.e., toward the +Z-axis direction side of the fifth wall 85. The seventh wall 87 is located on the +X-axis direction side of the sixth wall 86. The sixth wall 86 and the seventh wall 87 are provided at positions facing each other across the air chamber 68. The eighth wall 88 is located on the +Z-axis direction side of the fifth wall 85. The fifth wall 85 and the eighth wall 88 are provided at positions facing each other across the air chamber 68. The sixth wall 86 is arranged to intersect with both the fifth wall 85 and the eighth wall 88. The seventh wall 87 is also arranged to intersect with both the fifth wall 85 and the eighth wall 88.

The sixth wall 86, the seventh wall 87 and the eighth wall 88 are protruded in the -Y-axis direction from the first wall 81. A recess 99 is accordingly formed by the first wall 81 as main wall and the fifth wall 85, the sixth wall 86, the seventh wall 87 and the eighth wall 88 extended in the -Y-axis direction from the main wall. The recess 99 is formed to be concave in the +Y-axis direction. The recess 99 is open in the

-Y-axis direction, i.e., toward the sheet member 63 (shown in FIG. 5). In other words, the recess 99 is provided to be concave in the +Y-axis direction or more specifically to be concave in an opposite direction opposite to the sheet member 63-side (shown in FIG. 5). When the casing 61 is joined with the sheet member 63, the recess 99 is closed by the sheet member 63, so as to form the air chamber 68. The amounts of protrusion of the second wall 82 to the eighth wall 88 from the first wall 81 are set to an identical protrusion amount.

The second wall 82 and the sixth wall 86 form a step. The second wall 82 is located on the third wall 83-side of the sixth wall 86, i.e., on the +X-axis direction side of the sixth wall 86. The third wall 83 and the seventh wall 87 also form a step. The seventh wall 87 is located on the second wall 82-side of the third wall 83, i.e., on the -X-axis direction side of the third wall 83. In the plan view of the first wall 81 from the sheet member 63-side, an ink inlet portion 101 is placed between the third wall 83 and the seventh wall 87. The ink inlet portion 101 is provided on the fifth wall 85.

As shown in FIG. 7, the casing 61A has an extended portion 105. The communicating path 73 is provided in the extended portion 105. The extended portion 105 has a region 105A in an area of the fifth wall 85 on the +X-axis direction side of the seventh wall 87 to be extended in the +Z-axis direction from the fifth wall 85 along the periphery of the opening of the recess 91. The region 105A is also provided in the seventh wall 87 to be extended in the +X-axis direction from the seventh wall 87 along the periphery of the opening of the recess 99. The extended portion 105 also has a region 105B extended in the +Z-axis direction from the eighth wall 88. The extended portion 105 also has a region 105C in the sixth wall 86 to be extended in the -X-axis direction from the sixth wall 86 along the periphery of the opening of the recess 99. The extended portion 105 further has a region 105D in the second wall 82 to be extended in the -X-axis direction from the second wall 82 along the periphery of the opening of the recess 91. The communicating path 72 is formed as a groove 108 that is provided in the extended portion 105 to be concave in an opposite direction opposite to the sheet member 63-side (shown in FIG. 5).

As shown in FIG. 7, a recess 109 is provided in the recess 91. The recess 109 is surrounded by a ninth wall 111, a tenth wall 112, an eleventh wall 113 and the third wall 83. The recess 109 is provided to be concave from the fourth wall 84 toward an opposite side of the fourth wall 84 opposite to the fifth wall 85-side, i.e., to be concave in the -Z-axis direction from the fourth wall 84. The ninth wall 111 and the tenth wall 112 are provided on the fourth wall 84 to be protruded from the fourth wall 84 toward the opposite side of the fourth wall 84 opposite to the fifth wall 85-side, i.e., in the -Z-axis direction from the fourth wall 84.

The ninth wall 111 is located between the third wall 83 and the second wall 82 and is arranged to face the third wall 83 across the eleventh wall 113. The tenth wall 112 is located between the first wall 81 and the sheet member 63 (shown in FIG. 5) and is arranged to face the sheet member 63 across the eleventh wall 113. The eleventh wall 113 is located on an opposite side of the fourth wall 84 opposite to the fifth wall 85-side, i.e., on the -Z-axis direction side of the fourth wall 84. The eleventh wall 113 is arranged to face the fifth wall 85. The ninth wall 111 is arranged to intersect with the fourth wall 84, the tenth wall 112 and the eleventh wall 113. The tenth wall 112 is arranged to intersect with the fourth wall 84, the third wall 83 and the eleventh wall 113. The eleventh wall 113 is arranged to intersect with the third wall 83.

As shown in FIG. 7, the ninth wall 111, the tenth wall 112, the eleventh wall 113 and the third wall 83 surrounding the recess 109 form a supply assembly 114. The supply assembly 114 has a connection structure 115. The connection structure 115 is provided on the ninth wall 111. The connection structure 115 is located on an opposite side of the ninth wall 111 opposite to the recess 109-side. The connection structure 115 is protruded from the ninth wall 111 toward the opposite side of the ninth wall 111 opposite to the recess 109-side, i.e., from the ninth wall 111 toward the second wall 82. As shown in FIG. 8, the connection structure 115 is formed in a cylindrical shape. The connection structure 115 has a supply port 116. The supply port 116 is an opening formed on the connection structure 115 and serves as an outlet of ink from the tank 9A. The supply tube 43 (shown in FIG. 4) is connected with the connection structure 115. The ink contained in the tank 9A is fed from the connection structure 115 through the supply port 116 to the supply tube 43. The ink fed to the supply tube 43 is led through the supply tube 43 to the print head 47.

As shown in FIG. 7, an air communication structure 117 is provided on the eighth wall 88. The air communication structure 117 has an air communication port 118. The air communication port 118 is an opening formed on the air communication structure 117 to be open from the air communication structure 117 outward of the tank 9A. The air communication structure 117 is protruded from the eighth wall 88 toward an opposite side of the eighth wall 88 opposite to the fifth wall 85-side, i.e., on the +Z-axis direction side of the eighth wall 88. In the plan view of the eighth wall 88 or more specifically in the plan view of the eighth wall 88 on an XY plane, the air communication port 118 is provided at a position overlapping the recess 99. The air communication port 118 is arranged to make outside of the casing 61A communicate with inside of the recess 99. The air communication port 118 serves as an air flow path to introduce the air outside of the casing 61A into the inside of the recess 99. In the casing 61A, the joint portion 64 is provided along the outer shapes of the recess 91, the recess 99, the recess 109 and the communicating path 73.

As shown in FIG. 5, the sheet member 63 is arranged to face the first wall 81 across the second wall 82 to the eighth wall 88. In the plan view, the sheet member 63 has dimensions to cover the recess 91, the recess 99, the recess 109 and the extended portion 105 (shown in FIG. 7). The sheet member 63 is welded to the joint portion 64. Accordingly the recess 91, the recess 99, the recess 109 and the communicating path 73 are sealed by the sheet member 63. The sheet member 63 may thus also be regarded as a cover for the casing 61A.

As shown in FIG. 6, the communicating path 73 has a communication port 121 and another communication port 122. The communication port 121 is an opening that is open inward of the air chamber 68. The communication port 122 is an opening that is open inward of the container portion 65. The air chamber 68 communicates with the container portion 65 through the communication port 121, the communicating path 73 and the communication port 122. Accordingly, the container portion 65 communicates with outside of the tank 9A through the communicating path 73, the air chamber 68 and the air communication port 118. In other words, the communicating portion 67 makes the air communication port 118 communicate with the container portion 65. The air flowing from the air communication port 118 into the air chamber 68 is flowed through the communicating path 73 into the container portion 65.

The ink inlet portion 101 is provided on the fifth wall 85. As shown in FIG. 7, the ink inlet portion 101 is located in a recess 131 surrounded by the seventh wall 87, the extended portion 105, the third wall 83 and the first wall 81. As described above, the extended portion 105 is protruded toward the eighth wall 88-side of the fifth wall 85. The seventh wall 87 is also protruded toward the eighth wall 88-side of the fifth wall 85. Similarly, according to this embodiment, the first wall 81 and the third wall 83 are also protruded toward the eighth wall 88-side of the fifth wall 85. The extended portion 105 is arranged to intersect with both the seventh wall 87 and the third wall 83. The first wall 81 is arranged to intersect with both the third wall 83 and the seventh wall 87. Accordingly, an area of the fifth wall 85 on the third wall 83-side of the seventh wall 87 forms the recess 131 surrounded by the seventh wall 87, the extended portion 105, the third wall 83 and the first wall 81. The recess 131 is provided to be concave from the fifth wall 85-side toward the fourth wall 84-side.

The above configuration causes the ink inlet portion 101 to be surrounded by the seventh wall 87, the extended portion 105, the third wall 83 and the first wall 81. In other words, the ink inlet portion 101 is provided in the area of the fifth wall 85 surrounded by the seventh wall 87, the extended portion 105, the third wall 83 and the first wall 81. The recess 131 serves as an ink receiving portion. The ink receiving portion is configured to receive, for example, ink overflowing from the ink inlet portion 101 and ink dripping down in the course of pouring of ink. Accordingly, the recess 131 has the function of ink receiving portion to receive ink.

As shown in FIG. 5, a partition wall 125 is provided in the container portion 65. In the tank 9A, the partition wall 125 may be divided into a first partition wall 125A and a second partition wall 125B. The first partition wall 125A and the second partition wall 125B are continuous with each other via a bent part 127. The first partition wall 125A is located between the third wall 83 and the second wall 82 and is extended along the Z axis. The first partition wall 125A is connected with the fifth wall 85 on an opposite side to the bent part 127-side. The first partition wall 125A is located nearer to the third wall 83 than the second wall 82. The second partition wall 125B is located between the fifth wall 85 and the fourth wall 84 and is extended from the bent part 127 toward the second wall 82. The second partition wall 125B is inclined to be closer to the fourth wall 84 in a direction from the bent part 127-side toward the second wall 82-side.

As shown in FIG. 6, the partition wall 125 is provided on the first wall 81 and is protruded from the first wall 81 toward the sheet member 63 (shown in FIG. 4), i.e., in the -Y-axis direction. The partition wall 125 has a cutout 128 and another cutout 129. The cutout 128 and the cutout 129 are provided on an opposite side of the partition wall 125 opposite to the first wall 81-side, i.e., at an end on the sheet member 63-side (shown in FIG. 4). The cutout 128 and the cutout 129 are formed respectively to be concave from the sheet member 63-side (shown in FIG. 4) toward the first wall 81-side. The cutout 128 is provided on the first partition wall 125A.

The cutout 129 is provided on the second partition wall 125B. As shown in FIG. 5, the cutout 128 provided on the first partition wall 125A is extended from the fifth wall 85-side toward the fourth wall 84-side. The cutout 128 is connected with the fifth wall 85. The cutout 129 is provided between the bent part 127 and an opposite end of the second partition wall 125B opposite to the bent part 127-side. The joint portion 64 is provided in an area of the partition wall

125 between the cutout 128 and the cutout 129. The joint portion 64 is also provided in an area of the partition wall 125 on the second wall 82-side of the cutout 129. The sheet member 63 is also joined with the joint portion 64 of the partition wall 125. When the sheet member 63 is joined with the joint portion 64, clearances are formed at the positions of the cutout 128 and the cutout 129 between the sheet member 63 and the partition wall 125. A clearance is formed at the position of the cutout 128 between the fifth wall 85 and at least part of the partition wall 125. A clearance is formed at the position of the cutout 129 between the sheet member 63 and at least part of the partition wall 125.

As shown in FIG. 9 that is a sectional view of the ink inlet portion 101 and the air communication port 118 taken on an XZ plane, the ink inlet portion 101 has an opening 132 and a side wall 133. The opening 132 is a through hole formed in the fifth wall 85. The opening 132 is also an intersecting part at which the ink inlet portion 101 intersects with the container portion 65. The opening 132 intersects with the container portion 65 at the fifth wall 85. The ink inlet portion 101 may alternatively be configured to have the side wall 133 protruded inward of the container portion 65. In this modified configuration that the side wall 133 is protruded inward of the container portion 65, the intersecting part at which the ink inlet portion 101 intersects with the container portion 65 is also defined as the opening 132. The recess 91 communicates with outside of the recess 91 via the opening 132 that is the through hole. The side wall 133 is provided on an opposite side of the fifth wall 85 opposite to the fourth wall 84-side to surround the periphery of the opening 132 and form an ink pouring path. The side wall 133 is protruded from the fifth wall 85 toward the opposite side opposite to the fourth wall 84-side. According to this embodiment, the side wall 133 is protruded from the first wall 81 and the third wall 83 toward the opposite side opposite to the fourth wall 84-side. The side wall 133 serves to prevent the ink accumulated in the recess 131 from flowing into the opening 132.

In the tank 9A, as shown in FIG. 10 that is a side view of the tank 9A seen from the sheet member 63-side, ink 141 is contained in the container portion 65. For the better understanding of the configuration, the sheet member 63 is omitted from the illustration, and the joint portion 64 is hatched in FIG. 10. The ink 141 contained in the container portion 65 is supplied through the supply port 116 (shown in FIG. 8) formed on the connection structure 115 to the print head 47. According to this embodiment, in the use state of the liquid ejection system 1 for printing, the supply tube 43 is connected with the supply port 116, and the ink inlet portion 101 is closed by a cap 143. The ink 141 contained in the container portion 65 is flowed through the supply port 116 to reach the print head 47 by suction of the supply tube 43 via the relay unit 49.

With progress in printing by means of the print head 47, the ink 141 contained in the container portion 65 is fed toward the print head 47. Accordingly, the internal pressure of the container portion 65 decreases to be lower than the atmospheric pressure with progress in printing by means of the print head 47. As the internal pressure of the container portion 65 becomes lower than the atmospheric pressure, the air in the air chamber 68 flows through the communicating path 73 into the container portion 65. This is likely to maintain the internal pressure of the container portion 65 at the atmospheric pressure. The above configuration causes the ink 141 contained in the tank 9 to be supplied to the print head 47. When the remaining amount of the ink 141 is decreased with consumption of the ink 141 contained in the

11

container portion 65 of the tank 9, the operator is allowed to refill the container portion 65 with ink newly supplied from the ink inlet portion 101.

As described above, the partition wall 125 is provided in the container portion 65. Accordingly, the ink poured from the ink inlet portion 101 into the container portion 65 is guided by the partition wall 125 in a direction to be away from the third wall 83, i.e., in a direction from the third wall 83-side toward the second wall 82-side. This makes the ink poured from the ink inlet portion 101 into the container portion 65 unlikely to be directly poured on the third wall 83. This accordingly maintains the high optical transparency of the third wall 83 during pouring of ink from the ink inlet portion 101 into the container portion 65. As a result, this enables the liquid level of ink contained in the container portion 65 to be accurately reflected on the third wall 83 when ink is poured from the ink inlet portion 101 into the container portion 65. Accordingly this enables the liquid level of ink contained in the container portion 65 to be accurately recognized when ink is poured from the ink inlet portion 101 into the container portion 65.

The first partition wall 125A of the partition wall 125 is located on the third wall 83-side of the opening 132 that is the intersecting part of the ink inlet portion 101 and the fifth wall 85 as shown in FIG. 9. Accordingly, at least part of the partition wall 125 is located between the third wall 83 and the opening 132 that is the intersecting part of the ink inlet portion 101 and the fifth wall 85. When ink is poured from the ink inlet portion 101 into the container portion 65, the partition wall 125 interferes with the flow of the ink from the ink inlet portion 101 toward the third wall 83. Even when ink is splashed from the ink inlet portion 101 toward the third wall 83, this configuration reduces the likelihood that ink adheres to the third wall 83. This accordingly maintains the high optical transparency of the third wall 83 during pouring of ink from the ink inlet portion 101 into the container portion 65. As a result, this enables the liquid level of ink contained in the container portion 65 to be accurately reflected on the third wall 83 when ink is poured from the ink inlet portion 101 into the container portion 65. Accordingly this enables the liquid level of ink contained in the container portion 65 to be accurately recognized when ink is poured from the ink inlet portion 101 into the container portion 65.

In Embodiment 1, the container portion 65 corresponds to the liquid container portion; the ink inlet portion 101 corresponds to the liquid inlet portion, the fifth wall 85 corresponds to the first wall portion; the third wall 83 corresponds to the second wall portion; the fourth wall 84 corresponds to the bottom wall; the first wall 81 corresponds to the third wall portion; and the sheet member 63 corresponds to the fourth wall portion.

In the tank 9A, a clearance is formed at the position of the cutout 128 between the fifth wall 85 and at least part of the partition wall 125. This configuration makes the air trapped in a space surrounded by the fifth wall 85, the third wall 83, the first wall 81 and the sheet member 63 likely to be released through the clearance between the fifth wall 85 and at least part of the partition wall 125 during pouring of ink from the ink inlet portion 101 into the container portion 65. Accordingly, the liquid level of ink in the space surrounded by the fifth wall 85, the third wall 83, the first wall 81 and the sheet member 63 is likely to adequately rise during pouring of ink from the ink inlet portion 101 into the container portion 65. This configuration enables the liquid level of ink contained in the container portion 65 to be accurately recognized during pouring of ink from the ink inlet portion 101 into the container portion 65. As a result,

12

this enables the amount of ink contained in the container portion 65 to be accurately recognized.

In the tank 9A, a clearance is formed at the position of the cutout 129 between the sheet member 63 and at least part of the partition wall 125. This configuration makes the air trapped in the space surrounded by the fifth wall 85, the third wall 83, the first wall 81 and the sheet member 63 likely to be released through the clearance between the sheet member 63 and at least part of the partition wall 125 during pouring of ink from the ink inlet portion 101 into the container portion 65. Accordingly, the liquid level of ink in the space surrounded by the fifth wall 85, the third wall 83, the first wall 81 and the sheet member 63 is likely to adequately rise during pouring of ink from the ink inlet portion 101 into the container portion 65. This configuration enables the liquid level of ink contained in the container portion 65 to be accurately recognized during pouring of ink from the ink inlet portion 101 into the container portion 65. As a result, this enables the amount of ink contained in the container portion 65 to be accurately recognized.

In the tank 9A, as shown in FIG. 9, the distance between one end of the partition wall 125 on the third wall 83-side and the fifth wall 85 is smaller than the distance between the other end of the partition wall 125 on the opposite side to the third wall 83-side and the fifth wall 85. Accordingly, the partition wall 125 is arranged to be away from the fifth wall 85 in a direction from one end on the third wall 83-side toward the other end. This makes the ink poured from the ink inlet portion 101 into the container portion 65 likely to be away from the third wall 83. As a result, this makes the ink poured from the ink inlet portion 101 into the container portion 65 unlikely to be directly poured on the third wall 83.

In the tank 9A, as shown in FIG. 9, the second partition wall 125B of the partition wall 125 is located vertically below the opening 132 that is the intersecting part of the ink inlet portion 101 and the fifth wall 85. In other words, in the plan view of the opening 132 in the -Z-axis direction, at least part of the second partition wall 125B overlaps the opening 132. When the ink poured from the ink inlet portion 101 into the container portion 65 drips down in the vertical direction from the opening 132, the partition wall 125 reduces the impact of ink dripping and thereby reduces splash of the dripping ink. This is likely to suppress the dripping ink from being splashed and adhere to the third wall 83. As a result, this configuration enables the liquid level of ink contained in the container portion 65 to be accurately reflected on the third wall 83 during pouring of ink from the ink inlet portion 101 into the container portion 65. Accordingly this enables the liquid level of ink contained in the container portion 65 to be accurately recognized when ink is poured from the ink inlet portion 101 into the container portion 65.

The positions at which the cutout 128 and the cutout 129 are formed are not limited to the end on the sheet member 63-side. The cutout 128 and the cutout 129 may be provided on the first wall 81-side. The cutout 128 may be provided at any position that enables the air trapped between the third wall 83 and the partition wall 125 to be moved to the ink inlet portion 101 via the cutout 128 during pouring of ink from the ink inlet portion 101.

The partition wall 125 is not limited to the configuration that is divided into the first partition wall 125A and the second partition wall 125B but may have any configuration that allows the partition wall 125 to interfere with the flow of ink from the ink inlet portion 101 toward the third wall 83 when ink is poured from the ink inlet portion 101 into the

13

container portion **65**. The partition wall **125** may be configured, for example, to have only the first partition wall **125A**.

Embodiment 2

The following describes a tank **9B** according to Embodiment 2. The tank **9B** has a similar configuration to that of the tank **9A** of Embodiment 1, except the partition wall **125** of the tank **9A** of Embodiment 1. The like components of the tank **9B** to those of the tank **9A** are expressed by the like signs to those of Embodiment 1 and are not specifically described here. As shown in FIG. 11, the tank **9B** has a casing **61B** as one example of the tank main body and a sheet member **63**. The casing **61B** is made of a synthetic resin such as nylon or polypropylene. The sheet member **63** is identical with that of Embodiment 1 and is not specifically described here.

The casing **61B** is provided with a partition wall **151** placed in the container portion **65**. The partition wall **151** is continuous with the ink inlet portion **101** and is formed in a cylindrical shape. As shown in FIG. 12 that is a sectional view of the ink inlet portion and the air communication port taken on the XZ plane, the partition wall **151** is extended along the Z axis from an intersecting part **153** at which the ink inlet portion **101** intersects with the container portion **65**. The cylindrical partition wall **151** is connected with the fifth wall **85** and is extended from the fifth wall **85** toward the fourth wall **84**. The cylindrical partition wall **151** is arranged to surround the opening **132** of the ink inlet portion **101**. The intersecting part **153** is also defined as the opening **132** provided in the fifth wall **85**.

The tank **9B** employs the configuration that the side wall **133** is continuous with the partition wall **151**. The configuration of the partition wall **151** is, however, not limited to this configuration. For example, the partition wall **151** may be configured to surround the opening **132** from the outer side of the opening **132**. In this modified configuration, a step is formed between the side wall **133** and the partition wall **151**.

In the tank **9A** of Embodiment 2, the cylindrical partition wall **151** is likely to suppress the splash of ink from the ink inlet portion **101** toward the third wall **83** when ink is poured from the ink inlet portion **101** into the container portion **65**. This reduces the likelihood that ink adheres to the third wall **83**. This accordingly maintains the high optical transparency of the third wall **83** during pouring of ink from the ink inlet portion **101** into the container portion **65**. As a result, this enables the liquid level of ink contained in the container portion **65** to be accurately reflected on the third wall **83** when ink is poured from the ink inlet portion **101** into the container portion **65**. Accordingly this enables the liquid level of ink contained in the container portion **65** to be accurately recognized when ink is poured from the ink inlet portion **101** into the container portion **65**.

In Embodiment 2, the container portion **65** corresponds to the liquid container portion; the ink inlet portion **101** corresponds to the liquid inlet portion, the fifth wall **85** corresponds to the first wall portion; the third wall **83** corresponds to the second wall portion; the fourth wall **84** corresponds to the bottom wall; the first wall **81** corresponds to the third wall portion; and the sheet member **63** corresponds to the fourth wall portion. In the first aspect, the tank unit **5** corresponds to the liquid container unit.

In Embodiment 1 and Embodiment 2 described above, the third wall **83** inside of the container portion **65** may be configured to have enhanced liquid repellency against ink.

14

The third wall **83** of this configuration is likely to repel the ink even in the case that the splashed ink adheres to the third wall **83** during pouring of ink from the ink inlet portion **101** into the container portion **65**. This accordingly maintains the higher optical transparency of the third wall **83** during pouring of ink from the ink inlet portion **101** into the container portion **65**. As a result, this enables the liquid level of ink contained in the container portion **65** to be more accurately reflected on the third wall **83** when ink is poured from the ink inlet portion **101** into the container portion **65**. Accordingly this enables the liquid level of ink contained in the container portion **65** to be more accurately recognized when ink is poured from the ink inlet portion **101** into the container portion **65**.

One method employed to achieve the configuration of enhancing the liquid repellency against ink may be, for example, that the casing **61A** or the casing **61B** is made of a material having liquid repellency against ink. Another method employed to achieve the configuration of enhancing the liquid repellency against ink may be, for example, that a material having liquid repellency against ink (hereinafter called liquid repellent material) is applied on the third wall **83** inside of the container portion **65**. An example of the liquid repellent material may be a paint containing a fluororesin or a fluorine compound. The area in which the liquid repellent material is applied may be the entire area of the third wall **83** or part of the third wall **83**.

A method employed to apply the liquid repellent material on only part of the third wall **83** may apply the liquid repellent material on a partial area **155** in the width of the third wall **83** along the Y axis as shown in FIG. 13. In this configuration, for example, applying the liquid repellent material between the upper limit mark **28** and the lower limit mark **29** enhances the visibility of the liquid level of ink from the upper limit to the lower limit of the amount of ink. This method is not limited to the configuration that only one area **155** is provided on the third wall **83** but may employ a configuration that a plurality of areas **155** are arrayed along the Y axis on the third wall **83**.

Another method employed to apply the liquid repellent material on only part of the third wall **83** may apply the liquid repellent material on partial areas **157** in the height of the third wall **83** along the Z axis as shown in FIG. 14. In the illustrated example of FIG. 14, a plurality of areas **157** are arrayed along the Z axis. The intervals of the plurality of areas **157** arrayed along the Z axis may be equal or may be different.

In the configuration that the liquid repellent material is applied on only the partial areas **157** in the height of the third wall **83** along the Z axis, the plurality of areas **157** may have equal height dimensions **H1** or may have different height dimensions **H1** along the Z axis as shown in FIG. 15. In the illustrated example of FIG. 15, the plurality of areas **157** have different height dimensions **H1**.

In the configuration that the liquid repellent material is applied on only the partial areas **157** in the height of the third wall **83** along the Z axis, the liquid repellent material may be applied on an area **157A** including the upper limit mark **28** and an area **157B** including the lower limit mark **29** as shown in FIG. 16. This configuration facilitates at least the upper limit and the lower limit of the amount of ink to be accurately recognized.

(Second Aspect)

In the first aspect, the plurality of tanks **9** are not placed inside of the first casing **6** arrange to cover the mechanism unit **10**. In other words, the first aspect employs the configuration that the plurality of tanks **9** are placed outside of

15

the first casing 6. According to another configuration, the plurality of tanks 9 may be placed inside of the first casing 6. The following describes a multifunction printer as one example of the liquid ejection system according to a second aspect, with regard to the configuration that the plurality of tanks 9 are placed inside of a casing.

A multifunction printer 500 of this aspect includes a printer 503 and a scanner unit 505 as shown in FIG. 17. In the multifunction printer 500, the printer 503 and the scanner unit 505 are stacked. In the use state of the printer 503, the scanner unit 505 is placed vertically above the printer 503. XYZ axes as coordinate axes that are orthogonal to one another are shown in FIG. 17. The XYZ axes are also added as appropriate in subsequent drawings. The XYZ axes in FIG. 17 and the XYZ axes in the subsequent drawings are equivalent to the XYZ axis shown in FIG. 1. The like components of the multifunction printer 500 to those of the liquid ejection system 1 or the liquid ejection system 100 are expressed by the like signs to those of the liquid ejection system 1 or the liquid ejection system 100 and are not specifically described here.

The scanner unit 505 is flatbed type having an imaging element (not shown) such as an image sensor, a platen and a cover. The scanner unit 505 is capable of reading an image or the like recorded on a medium such as paper via the imaging element in the form of image data. The scanner unit 505 accordingly serves as a reader of the image or the like. As shown in FIG. 18, the scanner unit 505 is provided to be rotatable relative to a casing 507 of the printer 503. A printer 503-side surface of the platen of the scanner unit 505 also serves as a cover of the printer 503 to cover the casing 507 of the printer 503.

The printer 503 performs printing on a printing medium P such as printing paper with ink as one example of liquid. As shown in FIG. 19, the printer 503 includes the casing 507 and a plurality of tanks 9 as one example of the liquid container. The casing 507 is an integrally molded component that forms an outer shell of the printer 503 and includes a mechanism unit 511 of the printer 503. The plurality of tanks 9 are placed inside of the casing 507 to respectively contain inks used for printing. More specifically, the printer 503 has four tanks 9. The four tanks 9 respectively contain different inks. The printer 503 employs four different inks, i.e., black, yellow, magenta and cyan. Each of the four tanks 9 is provided to contain a different ink.

The printer 503 also has an operation panel 512. The operation panel 512 is provided with a power button 513 and other operation buttons 514. The operator who operates the printer 503 faces the operation panel 512 to operate the power button 513 and the operation buttons 514. A front surface of the printer 503 is a surface where the operation panel 512 is provided. The casing 507 has a window 515 provided on the front surface of the printer 503. The window 515 has optical transparency. The four tanks 9 described above are placed at a position overlapping the window 515. This configuration enables the operator to visually check the four tanks 9 through the window 515.

In the printer 503, a region of each of the tank 9 facing the window 515 has optical transparency. Ink contained in the tank 9 is visible through the region of each tank 9 having optical transparency. This enables the operator to observe the four tanks 9 through the window 515 and thereby visually check the amounts of inks contained in the respective tanks 9. In the printer 503, the window 515 is provided on the front surface of the printer 503. This configuration enables the operator facing the operation panel 512 to visually recognize the respective tanks 9 through the win-

16

dow 515. This accordingly enables the operator to check the remaining amounts of inks in the respective tanks 9 while operating the printer 503.

As shown in FIG. 20 that is a perspective view illustrating the mechanism unit 511, the printer 503 includes a printing assembly 41 and supply tubes 43. The printing assembly 41 and the supply tubes 43 have the similar configurations to those of the printing assembly 41 and the supply tubes 43 in the liquid ejection system 1 or in the liquid ejection system 100. Like the liquid ejection system 1 or the liquid ejection system 100, in the printer 503, the medium feeding mechanism drives a feed roller 51 with the power from a motor (not shown), so as to feed the printing medium P along the Y-axis direction. Like the liquid ejection system 1 or the liquid ejection system 100, in the printer 503, the head carrying mechanism transmits the power from a motor 53 via a timing belt 55 to a carriage 45, so as to carry the carriage 45 along the X-axis direction. The print head 47 is mounted on the carriage 45. The print head 47 is thus movable in the X-axis direction via the carriage 45 by the head carrying mechanism. The medium feeding mechanism and the head carrying mechanism cause ink to be ejected from the print head 47 while changing the position of the print head 47 relative to the printing medium P, so as to implement printing on the printing medium P.

In the respective aspects and embodiments described above, the liquid ejection apparatus may be a liquid ejection apparatus that sprays, ejects or applies and thereby consumes a liquid other than ink. The liquid ejected in the form of very small amounts of droplets from the liquid ejection apparatus may be in a granular shape, a teardrop shape or a tapered threadlike shape. The liquid herein may be any material consumed in the liquid ejection apparatus. The liquid may be any material in the liquid phase and may include liquid-state materials of high viscosity or low viscosity, sols, aqueous gels and other liquid-state materials including inorganic solvents, organic solvents, solutions, liquid resins and liquid metals (metal melts). The liquid is not limited to the liquid state as one of the three states of matter but includes solutions, dispersions and mixtures of the functional solid material particles, such as pigment particles or metal particles, solved in, dispersed in or mixed with a solvent. Typical examples of the liquid include liquid crystal, in addition to ink described in the above aspects and embodiments. The ink herein includes general water-based inks and oil-based inks, as well as various liquid compositions, such as gel inks and hot-melt inks. A concrete example of the liquid ejection apparatus may be a liquid ejection apparatus that ejects a liquid in the form of a dispersion or a solution containing a material such as an electrode material or a color material used for production of liquid crystal displays, EL (electroluminescent) displays, surface emission displays and color filters. The liquid ejection apparatus may also be a liquid ejection apparatus that ejects a bioorganic material used for manufacturing biochips, a liquid ejection apparatus that is used as a precision pipette and ejects a liquid as a sample, a printing apparatus or a microdispenser. Additionally, the liquid ejection apparatus may be a liquid ejection apparatus for pinpoint ejection of lubricating oil on precision machines such as machines and cameras or a liquid ejection apparatus that ejects a transparent resin solution of, for example, an ultraviolet curable resin, onto a substrate to manufacture a hemispherical microlens (optical lens) used for optical communication elements and the like. As another example, the liquid ejection apparatus may be a liquid ejection apparatus that ejects an acidic or alkaline etching solution to etch a substrate or the like.

According to one aspect of the embodiment, the liquid container comprises a liquid container portion that is configured to contain a liquid; and a liquid inlet portion that is connected with the liquid container portion and is configured to pour the liquid into the liquid container portion. The liquid container portion includes a first wall portion that is arranged to intersect with the liquid inlet portion; a second wall portion that has optical transparency and is arranged to intersect with the first wall portion; and a partition wall that is located between the second wall portion and an intersecting part at which the liquid inlet portion intersects with the first wall portion.

In the liquid container of this aspect, the partition wall interferes with the flow of the liquid from the liquid inlet portion toward the second wall portion when the liquid is poured from the liquid inlet portion into the liquid container portion. This configuration reduces the likelihood that the liquid adheres to the second wall portion even when the liquid is splashed from the liquid inlet portion toward the second wall portion. This facilitates the amount of the liquid contained in the liquid container to be recognized via the second wall portion.

In the liquid container of the above aspect, the liquid container portion may include a bottom wall that is located below the first wall portion in a state that the liquid container portion contains the liquid, and the partition wall may be extended in a direction from the first wall portion toward the bottom wall.

This aspect facilitates the wide area of the second wall portion to be blocked from the liquid inlet portion and thus makes the partition wall likely to interfere with the flow of the liquid from the liquid inlet portion toward the second wall portion.

In the liquid container of the above aspect, the liquid container portion may include a third wall portion that is arranged to intersect with the first wall portion and the second wall portion; and a fourth wall portion that is arranged to intersect with the first wall portion and the second wall portion. The partition wall may be a projection that is protruded from the third wall portion, and a clearance may be formed between at least part of the partition wall and the first wall portion.

This aspect makes the air trapped in a space surrounded by the first wall portion, the second wall portion, the partition wall, the third wall portion and the fourth wall portion likely to be released through the clearance between the partition wall and the first wall portion during pouring of the liquid from the liquid inlet portion into the liquid container portion. Accordingly, the liquid level in the space surrounded by the first wall portion, the second wall portion, the partition wall, the third wall portion and the fourth wall portion is likely to adequately rise according to the amount of the liquid poured from the liquid inlet portion. Accordingly this enables the amount of the liquid contained in the liquid container portion to be recognized accurately.

In the liquid container of the above aspect, the liquid container portion may include a third wall portion that is arranged to intersect with the first wall portion and the second wall portion; and a fourth wall portion that is arranged to intersect with the first wall portion and the second wall portion. The partition wall may be a projection that is protruded from the third wall portion, and a clearance may be formed between at least part of the partition wall and the fourth wall portion.

This aspect makes the air trapped in a space surrounded by the first wall portion, the second wall portion, the partition wall, the third wall portion and the fourth wall

portion likely to be released through the clearance between the partition wall and the fourth wall portion during pouring of the liquid from the liquid inlet portion into the liquid container portion. Accordingly, the liquid level in the space surrounded by the first wall portion, the second wall portion, the partition wall, the third wall portion and the fourth wall portion is likely to adequately rise according to the amount of the liquid poured from the liquid inlet portion. Accordingly this enables the amount of the liquid contained in the liquid container portion to be recognized accurately.

In the liquid container of the above aspect, a distance between one end of the partition wall on the intersecting part-side and the second wall portion may be less than a distance between the other end of the partition wall on an opposite side to the intersecting part side and the second wall portion.

In this aspect, the partition wall is arranged to be away from the second wall portion in a direction from one end on the intersecting part side to the other end. This configuration makes the liquid poured from the liquid inlet port likely to be away from the second wall portion and thereby reduces the likelihood that the liquid adheres to the second wall portion.

In the liquid container of the above aspect, at least part of the partition wall may be located vertically below the intersecting part in a state that the liquid is poured through the liquid inlet portion.

In this aspect, the partition wall serves to reduce the impact of liquid dripping when the liquid poured from the liquid inlet portion drips down in the vertical direction from the intersecting part. This accordingly reduces the splash of the dripping liquid. As a result, this further reduces the likelihood that the liquid adheres to the second wall portion.

In the liquid container of the above aspect, the partition wall may have a cylindrical structure, and the cylindrical structure may be extended from the intersecting part.

In this aspect, the cylindrical structure is likely to suppress the liquid from being splashed toward the second wall portion when the liquid is poured into the liquid container. As a result, this further reduces the likelihood that the liquid adheres to the second wall portion.

In the liquid container of the above aspect, a material having liquid repellency against the liquid may be applied on an inner wall of the second wall portion.

In this aspect, even when the liquid adheres to the second wall portion, the second wall portion is likely to repel the liquid. This is likely to maintain the visibility through the second wall portion and thereby further facilitates the amount of the liquid contained in the liquid container to be recognized via the second wall portion.

A liquid container unit comprises a cover, a support structure, and the liquid container according to any one of the above aspects 1 to 8 that is located between the cover and the support structure.

In the liquid container unit having the liquid container located between the cover and the support structure, this aspect facilitates the amount of the liquid contained in the liquid container to be recognized.

A liquid ejection system comprises the liquid container unit of the above aspect; a liquid ejection apparatus having a liquid ejection head; and a tube that is arranged to supply the liquid from the liquid container of the liquid container unit to the liquid ejection head. The liquid container unit is fixed to outer periphery of the liquid ejection apparatus.

19

In the liquid ejection system including the liquid container unit, the liquid ejection apparatus and the tube, this aspect facilitates the amount of the liquid contained in the liquid container to be recognized.

A liquid ejection apparatus comprises a cover; a support structure; the liquid container of any one of the above aspects that is located between the cover and the support structure; a liquid ejection head that is provided between the cover and the support structure; and a tube that is provided between the cover and the support structure and is arranged to supply the liquid from the liquid container to the liquid ejection head.

In the liquid ejection apparatus including the liquid container, the liquid ejection head and the tube, this aspect facilitates the amount of the liquid contained in the liquid container to be recognized.

The invention claimed is:

40 1. A liquid container comprising:

a liquid container portion configured to contain a liquid; a liquid inlet portion connected with the liquid container portion and allowing the liquid to be poured into the liquid container portion; and

45 an air communication port configured to introduce air into the liquid container portion, the liquid container portion including

a bottom wall,

a liquid inlet portion-forming wall that is located above the bottom wall and at which the liquid inlet portion is arranged,

50 a visual recognition wall that extends in a direction intersecting with the bottom wall and the liquid inlet portion-forming wall and through which the liquid in the liquid container portion is visible from outside, an opposite wall opposite to the visual recognition wall, and

55 a partition wall having an end portion apart from the opposite wall, at least a part of the partition wall being located between an opening and the visual recognition wall, the opening being an intersecting part at which the liquid inlet portion intersects with the liquid inlet portion-forming wall,

60 the liquid inlet portion being arranged closer to the visual recognition wall than to the opposite wall, and the air communication port being arranged closer to the opposite wall than to the visual recognition wall.

21

2. The liquid container according to claim 1, wherein the partition wall includes
- a first partition wall that is located between the visual recognition wall and the opposite wall and extends in a direction from the liquid inlet portion-forming wall toward the bottom wall, and
  - a second partition wall that is located between the liquid inlet portion-forming wall and the bottom wall and extends in a direction from the visual recognition wall toward the opposite wall, and
  - a part of the second partition wall is located below the opening in a vertical direction.
3. The liquid container according to claim 2, wherein the second partition wall is inclined to be closer to the bottom wall as approaching from the visual recognition wall toward the opposite wall.
4. The liquid container according to claim 1, wherein the partition wall has a cylindrical structure that extends from the intersecting part toward the bottom wall.
5. The liquid container according to claim 1, wherein a lower limit mark that indicates a lower limit of a liquid amount in the liquid container portion is disposed on the visual recognition wall.

22

6. The liquid container according to claim 5, wherein only an area of a part of the visual recognition wall has liquid repellency, and the area includes the lower limit mark.
7. The liquid container according to claim 1, wherein an upper limit mark that indicates an upper limit of a liquid amount in the liquid container portion is disposed on the visual recognition wall.
8. The liquid container according to claim 7, wherein only an area of a part of the visual recognition wall has liquid repellency, and the area includes the upper limit mark.
9. The liquid container according to claim 1, wherein only an area of a part of the visual recognition wall has liquid repellency.
10. A printer comprising:
the liquid container according to claim 1; and
a liquid ejection head,
the liquid container contained in a case of the printer, and
the case having a window portion that faces the visual recognition wall of the liquid container portion.
